HORSESHOE

Shawl J. Kelley, Baltimore, Md.

Application June 15, 1936, Serial No. 85,421

1 Claim. (Cl. 168—4)

The invention relates to horseshoes and more particularly to what are known as racing plates for use on race horses.

The invention may be considered as in the nature of an improvement on the general type of horseshoes disclosed in Kent Patents Nos. 530,643 and 553,586 which includes a body portion of light weight material such as aluminum and a steel insert. According to my invention 10 the steel insert comprises the toe calk of the shoe.

One of the objects of my invention is to provide an improved insert within the body portion. Another object is to provide an improved toe 15 plate or calk for the shoe.

The invention will be more readily understood by reference to the accompanying drawing and the following detailed description in which are set forth an illustrative improvement of the inventive thought.

In the drawing:

Fig. 1 is a bottom view of the improved racing plate.

Fig. 2 is a section on line 2—2 of Fig. 1.

Fig. 3 is a front view of the plate.

Fig. 4 is a section on line 4—4 of Fig. 2, showing the manner in which the steel insert is held in position.

Fig. 5 is a section on line 5—5 of Fig. 1.

Fig. 6 is an elevation of the steel insert or toe calk shown separate from the racing plate.

Fig. 7 is a top view of the same.

Fig. 8 is a section on the line 8—8 of Fig. 7.

Referring to the drawing, A denotes the main body of the shoe which is preferably composed of light weight material such as aluminum. Bar stock $\frac{1}{4}$ inch by $\frac{1}{2}$ inch in size may be cut to the right length according to the size of the shoe desired and bent to the proper shape to fit the 40 shape of the forging die.

The reference character B denotes an insert or toe calk composed of suitable wear resisting material preferably steel. This insert may be composed of metal $\frac{3}{4}$ of an inch thick by $\frac{1}{8}$ of an inch wide cut to the length desired, which may vary according to the size and style of the shoe.

The member B is then passed through bending and crimping dies whereby it is given an arcuate configuration and a crimped portion 10 at the bottom. The toe is then placed in the forging die and the aluminum body member A is brought to a temperature of approximately 900° at which temperature the metal becomes plastic or gelatinous. It is then placed in the die on a crank 55 press and pressed to shape under a pressure of

approximately 300 tons. The upper face of the plate is flat as indicated at 11 while the lower or ground engaging face is inclined and is convex throughout the major portion of its extent as illustrated at 12 in Fig. 5 and in the shaded portion in Fig. 1. It will be noted that the convex portions 12 of the shoe are located at the sides of the shoe and slope gradually from a raised outer rim 14 to the interior of the shoe. Intermediate the convex side portions there is 10 a built-up toe portion 13 which in the complete shoe is of substantially greater thickness than the side portions and serves to firmly hold the steel toe calk B in place as is apparent from Fig. 2, the insert being preferably of substantially the 15 same length as the raised or built-up reinforcing portion 13.

After the shoe A has been shaped and while still hot and plastic the crimped root portion of the toe B is pressed into the shoe, the metal 20 which is pressed in around the crimped portion serving to hold the plate solid.

The shoe is then trimmed by means of suitable trimming dies after which nail holes 15 are formed in the shoe adjacent the rim 14. These 25 holes are of any suitable shape to receive standard horseshoe nails. The bottom of the plate is then ground to remove burrs caused by piercing the nail holes.

The toe is ground at the outside to produce a 30 bevel 16 preferably corresponding in inclination to the inclined front portion 11 of the shoe. The inside of the toe plate is straight. This arrangement gives the horse a straight pull to the ground, while if the horse should jump or strike a horse 35 in front of him the outside bevel will release instead of cutting off the tendon as would be the case with those shoes which are made at the present time that are beveled on the inside.

The invention has been described in detail for 40 the purpose of illustration but it will be apparent that variations and modifications may be resorted to without departing from the spirit of the invention.

I claim:

A racing horse-shoe comprising a body member formed of light weight material shaped to fit the foot of the horse, said body member having a raised rim and side portions whose ground engaging faces are convex and slope gradually 50 from the raised rim toward the interior, a built-up toe portion intermediate the side portions of substantially greater thickness than the side portions, and a steel insert at the rim of the toe portion forced into the body member while said 55

body member is hot and plastic, said insert having a crimped root portion anchored within the metal of the body member the exposed portion of said insert being vertical on the inside and beveled on the outside, the bevel sloping from the tip of the insert toward the body member, said

insert being of substantially the same length as the built-up toe portion of the body member, and being braced by the extra thickness of said built-up portion.

SHAWL J. KELLEY.
